LLOYD GROFF COPEMAN, OF FLINT, MICHIGAN, ASSIGNOR TO COPEMAN ELECTRIC STOVE COMPANY, OF FLINT, MICHIGAN, A CORPORATION OF MICHIGAN.

ELECTROMAGNETIC SWITCH.

1,141,174.

Specification of Letters Patent.

Patented June 1, 1915.

Application filed July 28, 1911. Serial No. 641,004.

To all whom it may concern:

Be it known that I, LLOYD GROFF COPEMAN, a citizen of the United States of America, residing at Flint, in the county of Genesee and State of Michigan, have invented 5 certain new and useful Improvements in Electromagnetic Switches, of which the following is a specification, reference being had therein to the accompanying drawings.

10 The invention relates to automatic electrical circuit breakers, and is more particularly designed for use in connection with electric cookers.

15 It is the object of the invention to obtain a reliable construction which is small and inexpensive to manufacture and which is particularly adapted to fill the requirements of the apparatus in connection with which it is used, as more fully hereinafter set forth.

20 In the drawings,—Figure 1 is an elevation of the circuit breaker as arranged in connection with an electric cooking range; Fig. 2 is a perspective view thereof; and Fig. 3 is a front elevation.

25 A is a base which is provided at its upper end with a shelf or bracket B forming the support for one or more depending electromagnets C. These are preferably arranged in pairs to form a horseshoe construction, 30 the bridge between the two being formed by the shelf B which is preferably of magnetic metal.

35 D is an electric switch arranged beneath the magnet C and provided with a hinged blade E pivotally connected at its lower end with a post F. This post is mounted upon an insulator plate G which forms a facing for the base plate A, and a second post H is secured to said insulator plate extending outward in proximity to the free end of the 40 blade E.

45 I is a contact plate adapted to abut against a contact plate I' on the end of the post H and yieldably secured to the inner side of the blade E. As shown, this contact I is secured to a resilient strip J which is attached at K to the blade and has a projecting portion L bent to contact with the post F and under tension to press the blade E 50 outward. The blade E is normally held in

position to close the circuit by a latch member M which engages the free end thereof, said latch member being pivotally mounted at N to the base plate A.

O is an armature for the electromagnet C 55 which is guided by engaging pins P of non-magnetic metal projecting downward from the poles of the magnet and engaging apertures in the armature.

Q are stop pins for limiting the downward movement of the armature, and R is a central pin for connecting said armature to the latch M, an insulating bushing S being used to break electrical connection.

50 The switch constructed as described is 65 preferably mounted inside of the cabinet containing the electric cooker, but a handle T projecting outward from the blade E passes through the slot U in this cabinet. Thus the switch may be closed by lifting the 70 handle T through the medium of an insulator knob V, and when the contact I is pressed against the post H by the resilient strip J the latch M will engage the blade E and hold it from outward movement. In this 75 position of parts the switch will remain closed until the electromagnet C is energized, preferably through the medium of a suitable thermostatic control (not shown) which will lift the armature and latch, disengaging the blade E and permitting gravity assisted by the tension of the spring L to 80 open the switch.

85 With certain constructions of apparatus, the switch may be most conveniently located near the base of the cabinet, and in this position it may be operated without the necessity of bending over by lifting the knob V with the foot.

90 The latch is gravity actuated, and by reason of its loose connection with the guide pins P is always in position for engagement with the blade E. The contact plate I abuts against the post H and therefore does not tend to hold the blade from movement as 95 might be the case with the knife switch, so that the certainty of operation is insured.

95 What I claim as my invention is:

100 In an electric switch, the combination with an insulator base, of a post projecting there-

from, a switch blade pivotally connected to said post, a resilient strip secured to said blade, a contact member upon said strip, a coöperating post against which said contact member is adapted to be pressed by said switch blade, a second resilient strip secured to said blade having a projecting portion in contact with the post projecting from said

base, and a common securing means for both of said resilient strips.

In testimony whereof I affix my signature in presence of two witnesses.

LLOYD GROFF COPEMAN
